UNITED STATES PATENT OFFICE.

JOHN E. JOHNSON, OF CHICAGO, ILLINOIS, ASSIGNOR TO THE SPEEDAUTOMATIC COMPANY, OF CHICAGO, ILLINOIS, A CORPORATION OF DELAWARE.

COPYHOLDER.

Application filed January 20, 1923. Serial No. 613,807.

This invention relates to a device of the type known as copy-holders for holding manuscripts or other papers, cards, or sheets from which written matter or data is to be copied. This form of device is capable of use under a variety of conditions, such for example as in connection with type-writing or type-setting.

A particular object of this invention is to provide a holder of the above indicated type, which will enable the user to read and copy any portion of a long list of items easily and accurately.

Another object of the invention is to provide a ready means for marking any particular place or line which is being copied, in order to avoid unnecessary skipping or repeating of any of the subject matter.

A still further object is to provide a holder that can be readily adapted to hold a variety of sheets of paper of different sizes and shapes, such as long lists of data, note books, or a plurality of cards of any desired shape or size.

A further object of the invention is to provide a device of the type indicated, which is durable and simple in construction and which is convenient in operation. Other objects will appear from the following specification and claims and the accompanying drawings, in which—

Figure 1 is a front elevation of a preferred form of the invention, showing the device in operative position;

Fig. 2 is a perspective view of a tray, which is adapted to be secured to the copy-holder for holding cards;

Fig. 3 is a side elevation looking from the right at the device as shown in Fig. 1;

Fig. 4 is a sectional view on line 4—4 of Fig. 1; and,

Fig. 5 is a perspective view showing the tray of Fig. 2 and the line marker in operative position.

The preferred form of the device may comprise in a general way an inclined plate 1 upon which sheets of paper, as indicated at 2, may be mounted, an adjusting and retaining mechanism 3 for adjustably retaining the paper in position, a line marker 4 and a card tray 5, which may be detachably mounted upon the plate 1 and serves to hold groups of cards, or the like.

The inclined plate 1, as shown, is provided at the center of its back with a chan-

nel member 6, into which a flattened angularly disposed end 7 of a supporting rod 8 may be removably inserted. A pedestal 9 has an opening 10 into which the lower end of the supporting rod 8 may be inserted and adjustably clamped at a desired elevation by a thumb screw 11.

At the upper side of the plate 1, a bracket 12 may be provided which serves to support the adjusting mechanism 3 and also a rod 13 upon which the line marker 4 is mounted. The lower end of the rod 13 is shown retained in a bracket 14, riveted at 15 to the plate 1.

As indicated in Fig. 5, the line marker 4 may be riveted at 16^a to a sliding bracket 16, having integral bent up lugs 17 and 18, each provided with openings for the rod 13. The lug 18 may be slightly extended to provide a handle 19. A small flat spring 20 is shown riveted at 21 to the base portion of the bracket 16 and serves to hold the bracket 16 frictionally in place upon the rod 13. It will thus be seen that the line marker 4 may be adjusted at any desired position upon the plate 1 by the operator by merely grasping the handle 19 and moving it up and down along the bar 13.

In the lower portion of plate 1, two slots 22 and 23 are shown which are engaged by lugs 24 and 25, respectively, formed upon the tray 5. The tray 5, as shown, comprises merely a base portion 26 and a back portion 27 which serve to hold a group of cards or the like, as indicated at 28. With this construction, it will be obvious that if it is desired to use long sheets of paper upon the plate 1, the tray 5 may be removed and will not obstruct the proper use of the surface of the plate 1. However, when it is desired to copy information from a series of cards, the tray 5 may be readily attached in place. It will be noted that the plate 1 is slightly inclined in a backward direction which not only permits of more secure mounting and reading of the manuscripts thereon, but also permits the card tray 5 and cards to rest in a stable inclined position.

The adjusting mechanism 3 comprises a shaft 29 rotatably mounted in lugs 30 and 31 formed upon the bracket 12, which in turn is secured to the upper edge of the plate 1 by rivets 32 and 33. Rollers 34 and 35 are fixed upon the shaft 29 and may be ro-

2
tated by turning a knob 36 which is fixed to the shaft 12 by a set screw 37.

The bracket 12 is provided with a supporting rod 38 which extends along the top and front of the plate 1 and serves to support a spring 39, which is secured thereto by screws 40. The spring 39 is coiled about the rod 38 at spaced points in opposite directions and terminates in arm portions 41, which serve to yieldingly support a shaft 42. Rollers 43 and 44 are rotatably mounted on the shaft 42 and are spaced apart by a spacing sleeve 45 which surrounds the shaft 42. The arm portions 41 are bent to conform to the exterior of the sleeve 45 and serve to hold this sleeve on the shaft securely in position. The ends of the shaft 42 may be enlarged or headed as at 46 in order to retain the rollers 43 and 44 in position.

The paper or manuscript 2 is fed between the pairs of rollers 34 and 35, and 43 and 44 and is frictionally engaged therebetween at the desired elevation. It will thus be seen that with this type of construction, a very long or even a continuous sheet of copy may be conveniently led into the device as at 48 and out from the device as at 49. In order to change the line marker 4 from one line or point on the paper to another, either the marker may be moved by handle 19 or the position of the paper may be adjusted by turning knob 36. Thus the operator can easily adjust the device to copy a certain line regardless of the position of the paper, by moving the marker, or if desirable, regardless of the position of the line marker 4, by moving the paper.

I desire that my invention be broadly interpreted and limited only by the scope of the appended claims and the prior art.

What I claim as new and desire to secure by Letters Patent in the United States is:

1. A copy-holder comprising a manuscript supporting plate, a rotatable means over which the manuscript is turned at the upper edge of said plate, a second rotatable means for holding the manuscript against said first means, and fixed spring means which supports and urges said second, rotatable means against said first rotatable means to releasably retain the manuscript therebetween.

2. A copy-holder comprising a manuscript supporting plate, a rotatable means over which the manuscript is turned at the upper edge of said plate, a second rotatable means for holding the manuscript against said first means, and fixed spring means which supports and urges said second rotatable means against said first rotatable means to releasably retain the manuscript therebetween, said spring means comprising a wire coiled about a fixed shaft and extending to and engaging said second rotatable means at spaced points.

3. A copy-holder comprising a manuscript supporting plate, a rotatable means over which the manuscript is turned at the upper edge of said plate, a second rotatable means for holding the manuscript against said first means, and spring means which supports and urges said second rotatable means against said first, rotatable means to releasably retain the manuscript therebetween, said spring means comprising a wire coiled around a fixed support and then extending to said second rotatable means.

4. A copy-holder comprising a manuscript supporting plate, a rotatable means over which the manuscript is turned at the upper edge of said plate, a second rotatable means for holding the manuscript against said first means, and fixedly mounted spring arms for supporting and urging said second rotatable means against said first rotatable means to releasably retain the manuscript therebetween.

5. A copy-holder comprising a manuscript supporting plate, a rotatable means over which the manuscript is turned at the upper edge of said plate, a second rotatable means for holding the manuscript against said first means, and spring arms for supporting and urging said second rotatable means against said first rotatable means to releasably retain the manuscript therebetween, said spring arms comprising an integral length of wire coiled around a fixed support at spaced points and the ends of the wire extending to said second rotatable means and forming the supporting arms therefor.

In witness whereof, I have hereunto subscribed my name.

JOHN E. JOHNSON.
